JOHN F. ENGLE, OF CLEVELAND, OHIO.

SELECTIVE SYSTEM AND APPARATUS.

1,156,852.

Specification of Letters Patent.

Patented Oct. 12, 1915.

Application filed May 5, 1909. Serial No. 494,078.

To all whom it may concern:

Be it known that I, JOHN F. ENGLE, a citizen of the United States of America, and a resident of Cleveland, in the county of Cuyahoga and State of Ohio, have invented certain new and useful Improvements in Selective Systems and Apparatus, (Case 3,) of which the following is a specification.

My invention relates to improvements in selective signaling systems and apparatus, and has for its object the provision of means for signaling any one of a relatively large number of stations connected upon the same electric circuit.

Individual selective signaling for a limited number of stations has previously been accomplished in a number of different ways, of which those actuated by currents of different frequencies appear to be the most practical and commonly used. My invention, however, is designed more particularly for selectively signaling any one of many stations upon a telephone line, and the conditions are such that harmonic currents in association with bridged bell circuits, not only would be undesirable, but the range of harmonic selection would not be sufficiently great. Neither am I acquainted with any system involving the relative strength of the actuating batteries, or the change of their polarity, which will permit of the wide range of selection obtainable by the improvement herein described.

The principle of operation utilized herein, is the provision of a circuit-controlling apparatus at each station, which is provided with a plurality of circuit-closing members serially arranged in the signaling or local circuit. These circuit-closing members are universally actuated from the central office, but the electrical connections of each are so varied, that only one signaling circuit is adapted to be closed during a given relation of the circuit-closing members. Various means may be provided for effecting the signal under these circumstances, but I have shown and herein described, a local circuit at each of the several stations which contains a battery and make and break bell.

Inasmuch as my improvements comprise essentially a single central station, and a plurality of stations to be selected, all of the latter being identical in character, I can explain my invention by making reference to a central station, associated with a

single selected station as typical of all the others.

Referring to the drawings:—Figure I illustrates diagrammatically at A, the central station, or signaling office of a telephone line, with the apparatus required for the actuation of the system; while B in a similar diagrammatic manner, illustrates the station apparatus at one station of the many which it will be understood may be connected with the central or selecting station. Fig. II is a somewhat diagrammatic cross-sectional view of a part of the selecting apparatus. Fig. III shows a detail of parts of one of the selecting switches; and Fig. IV is another diagrammatic detail, illustrating the manner in which the local circuit is closed by the proper selecting switch.

Throughout the several figures of the drawings, I have indicated similar parts by the same character of reference, in order to avoid confusion in referring thereto.

Mere inspection of the drawings will indicate that the apparatus herein shown is of the step-by-step type, controllable over the two limbs of the metallic circuit, which preferably is not intermediately grounded. The improvements center, however, in the peculiar type of selecting switch, which I may term "permutating"; shown in the upper part of Fig. I, and diagrammatic details thereof appear in Figs. III and IV.

The main battery b is intermediately grounded at the central office, and its two poles are respectively carried to terminals 90 upon the selector appliance a. This is provided with as many keys 7, 8, etc., as there are stations to be selected, and as many contact bars a' to a'', as there are switch spring sets in each of the selector-switches at the several sub-stations. An additional bar a''' is also provided, which is adapted to be engaged by any one of the rear row of key-mounted contacts, when its respective key is depressed.

Referring to Fig. II, it is seen that the key 7 is spring mounted and rearwardly insulated in the strip c' of the frame c. A downward movement of the key will engage the four contact pins 7'', 7', 7⁴ and 7⁶ with the respective contact bars of said appliance a, and also close circuit between the spring c² and its co-acting contact c³, the latter being connected with the positive pole of the battery. This serves to supply current 110

through the key lever and the engaging contacts, to the bars a'' , a' , a^4 and a^6 . Contact bar a'' is connected directly with the interrupter d , which immediately is energized to supply positive interrupted currents by way of conductor $1'$ to one side 1 of the line. The polarized actuating electro-magnets e , e' , etc., are serially connected with conductor 1 at the central station, and at each of the sub-stations respectively, for controlling the step-by-step apparatus there positioned.

The magnets e , e' , etc., at each impulse from the interrupter, will respectively close the local circuit from batteries b' , b'' , etc., through the corresponding step-by-step magnets f' , f'' , etc., through the simultaneous actuation of their armature contacts to the right.

The central office step-by-step mechanism g , and the corresponding associated switch mechanism h at each of the stations on the line, are advanced one step for each impulse thus automatically transmitted. With the former, the contacts g' to g^6 are respectively engaged in succession by the arm g'' , which is directly connected with limb 2 of the outgoing line, and concurrently each of the switch members h' , which consists of a plurality of sets of switch springs, electrically separated from each other, but mechanically fixed *en masse* to a movable member, will be caused to rotate upon its pivot h'' , to effect changes respectively in the local circuits of their co-acting alarm bells j . The action described, is readily effected by means of the ratchet and pawl, respectively associated with these members and their actuating magnets.

To obtain an understanding of the operation, it will be necessary to refer to the features of switch h . In the example shown, each switch is provided with six sets of contact springs; all of which are normally out of contact, although the various springs in each set are rearwardly connected up to effect the permutation or change in the local circuit controlled. These connections obviously differ in each switch of a given system. However, said switches by their construction, are capable of variable normal connections adapting them for interchangeable use at any of the several stations of the system. Each set of springs comprises an intermediate or longer spring, and two co-acting shorter springs respectively positioned above and below the long or actuated spring. These long springs i' to i^6 extend in position to be swept successively beneath the armature m' of an electro-magnet m serially connected in limb 2 of the line. In the continued path of their travel is positioned the arc i'' of insulating material; the relation of these parts being best gathered by referring to Figs. I and III.

As the pivoted members h' are advanced step-by-step, the long springs i' to i^6 will

successively ride upon the inclined surface of the insulating guide or arc i'' , and thereby be forced into contact with their co-acting upper springs, unless the armature m' , which has a downwardly inclined engaging face, shall be depressed to the dotted line position shown in Fig. III. In this event, the long springs which are thus depressed, will pass beneath the arc i'' , and will engage or close circuit with the lower contact springs in their respective sets. Thus, it will be seen that the local circuit, wherein these springs are serially connected, must be closed at six or more points, in order to actuate the alarm bell j , which is of the interrupter type. It is obvious that the several sets of springs, i' , i^2 , i^3 , etc., might be wired differently so that each of the sets would control a local signaling or other circuit. In fact, quite a number of different wiring combinations might be arranged by one skilled in the art. In addition, there is a seventh contact to be closed in the local circuit, viz: contact spring n , which is adapted upon the final step of each switch to engage with the stud n' , and close contact therewith. This is important, for the reason that none of the local circuits should be closed at the respective stations until final steps of switch h , and of the rotator g have been effected. Upon depressing key 7, it will be remembered that positive current was supplied to three of the contact parts corresponding to and connected with the contacts g' , g^4 and g^6 of the rotator g , and in consequence, as the respective segments are engaged by the contact arm g'' as it is swept over said segments from right to left, positive current impulses will be intermittently transmitted over limb 2 of the line, and through the windings of the connected electro-magnets m . Thus, upon the first step of each of the switches h , the armature m' of each magnet m , will be depressed, thereby causing the long spring i' to pass beneath the arc i'' , and flex it into contact with the lowermost spring of its set. Upon the next two impulses or steps of the switching apparatus h , the long springs i^2 and i^3 , will engage the inclined edge of arc i'' , and ride upon its upper face, thereby engaging said springs respectively with the upper contact springs of the corresponding sets. Upon taking the next or fourth step, and upon the sixth step as well, the magnet m will again be energized to depress the long springs i^4 , i^5 and cause them to pass beneath arc i'' , while spring i^6 , being uninfluenced by the armature m' , will ride upon the arc i'' , and contact then being closed with spring n , the local circuit through the bell, will be established at station 7 or B, as indicated in Fig. IV. In this figure, the horizontally positioned springs are arranged vertically, in order to show both their

permanent rearward connection, and the flexure of the three long springs i' , i^4 and i^5 into contact with the corresponding upper springs of their sets; the remaining springs, 5 as normally occurs, being engaged with the lower springs of their sets. For this purpose the unitary arc i'' is shown in cross-section at six different places to illustrate the electrical connection of the parts. Under 10 these circumstances, the alarm bell will be rung by the local battery at the selected station, until the local circuit is broken by the restoration of switch h , which takes place simultaneously at all the stations.

15 To call station 8, for example, it is seen that the contact parts in the corresponding key 8, are arranged to make connection with bars a'' , a' , a^3 and a^5 , and the switch at station 8 (not shown) must be permanently 20 connected to effect a closure of the local circuit upon the engagement of springs i' , i^3 and i^5 with the lower contacts of their respective sets and the simultaneous closure of the springs i' , i^4 , and i^5 with the upper 25 springs of their respective sets. In this manner, the selection of a large number of stations may be readily arranged for.

From the foregoing, it will be understood 30 that the circuit connections of each of the permutating switches h must vary at each of the stations to be selected, which is readily accomplished by rearwardly connecting the long springs permanently with the short springs of the adjacent sets in the variety 35 of combinations thus afforded. Inasmuch as each of the switches must assume the same mechanical relation upon the depression of any key, it will be appreciated that the differences for effecting the selective signaling must reside in the local circuit 40 connections, established through the variously actuated, and permanently connected contact springs. All this is controlled by the position of the contact studs in the respective key levers, and a very large number of 45 circuit changes may be provided for, with the use of a relatively small number of spring sets upon each permutating switch. The number of such sets obviously may be 50 varied, if desired.

To effect a restoration to normal conditions, the key lever which has been depressed, as 7, will be momentarily raised by the central office operator, preferably when 55 the selected station has responded, thereby engaging contact spring c^4 with its stud c^5 , and contact spring c^6 , with its stud c^7 . The contact stud c^5 is permanently connected with the negative side of the battery b , and 60 in consequence, negative current will be momentarily transmitted over conductor 1' and limb 1 of the line, thereby exciting the polarized magnets e , e' , etc., to engage with their left-hand contacts, and close the local 65 circuits respectively through the restoring

magnets o , o' , etc. These act respectively upon the latches o'' , engaging the rotary ratchets g , h' , and the ends of their respective actuating pawls, so that the restoring magnets momentarily release said ratchets, 70 and permit the switches h and rotator g , to be restored by their respective tension springs. The apparatus is then in position for the selection of any other station desired. Common restoring key r may be provided in lieu of the foregoing arrangement, 75 if desired, which is adapted to throw negative current directly upon limb 1 of the line, and actuate the magnets o , o' , etc.

Each of the magnets e' and m at the 80 several stations, is bridged by a condenser p , p' . Across the terminals of the latter are placed the emergency switches or cut-outs k , k' . Telephone sets t , t' , t^2 are also diagrammatically indicated as bridged across 85 the line, merely to suggest the purpose for which the selective apparatus is primarily designed, but these form no part of my invention and are here alluded to merely as explanatory of one adaptation thereof.

In the claims, I have referred to the sub-station switch as one adapted for permutative connection, and have further defined it as a permutating switch; meaning thereby a switch of the general type herein set forth 90 for use at each party line station, which switch is provided with contact parts capable of electrical transposition or arrangement in different concerted connective relation.

Having now explained in brief, in connection with the diagrammatic drawings, a system and apparatus for practising my invention, I hereby claim the same, without necessarily restricting myself to the details 100 herein set forth, in the following terms:—

1. In selective switching apparatus, the combination with a switch of the class described, comprising a plurality of sets of contracts, of a circuit including an electromagnet, and means operated thereby for effecting the bodily movement of said switch, and a second circuit including an electromagnet, and means governed thereby for selecting certain contacts from each set and 110 closing all of said selected contacts in series as said bodily movement takes place, substantially as set forth.

2. A selective signaling system, comprising two line conductors, circuit-controlling apparatus and a source of electrical energy associated therewith at a central office, a plurality of sub-stations adapted to be individually selected thereby, each equipped with a permutating switch comprising a plurality 120 of separable contacts through each of which a signaling circuit is adapted to close in series relation, an electro-magnet controllable over one line conductor and means operated thereby for effecting the actuation of said 130

switch, and a second electro-magnet controllable over the other line conductor and means operated thereby for modifying the electrical relations of the permutating switch contacts, substantially as set forth.

3. In apparatus of the class described, the combination with a rotary member, of a plurality of separable switch contacts mounted thereon through which a circuit is adapted 10 to be established in series relation, an electromagnetic means for advancing the rotary member step-by-step, a second electro-magnetic means adapted to modify the electrical relation of said contacts, and circuit-controlling apparatus for actuating the switch contacts, substantially as set forth.

4. In a selective signaling system, the combination with the line conductors thereof, of a source of electrical energy and suitable circuit-controlling apparatus associated therewith, a plurality of stations connected with said line conductors, each of which is equipped with a permutating switch, comprising a rotary member, a plurality of differently connected separable switch contacts mounted thereon through which a circuit is adapted to be established in series relation, an electro-magnet and means operated thereby for advancing the rotary member step-by-step, and a second electro-magnet and means operated thereby adapted to modify the electrical relation of said contacts, said magnets being respectively controllable over the line conductors, substantially as set forth.

5. In a selective signaling system, the combination with the line conductors thereof, of a source of electrical energy and suitable circuit-controlling apparatus associated therewith, a plurality of stations connected with said line conductors, each of which is equipped with a permutating switch, comprising a rotary member, a plurality of differently connected separable switch contacts 45 mounted thereon through which a circuit is adapted to be established in series relation, an electro-magnet and means operated thereby for advancing the rotary member step-by-step, a second electro-magnet and means 50 operated thereby adapted to modify the electrical relation of said contacts, and a restoring electro-magnet for returning the apparatus to its initial position, said magnets being respectively controllable over the line 55 conductors, substantially as set forth.

6. In a permutating switch of the class described, the combination with a plurality of sets of contact members arranged in different planes and adapted to be permutatively connected, of an engaging member adapted to actuate said contact members into different electrical relations, and electro-magnetic means for effecting their relative movement to complete the control of a 65 connected circuit under predetermined conditions of actuation, substantially as set forth.

7. In a permutating switch of the class described, the combination with a plurality of sets of switch springs, the individual 70 springs of each set being disposed in different planes and alternatively adapted to be actuated into electrical contact, means for alternating their normal connections, an engaging member for said switch springs, 75 and means for effecting the relative movement of said switch-springs and member, whereby said switch springs are actuated into different electrical relation and a circuit may be closed therethrough under pre-determined conditions, substantially as set forth.

8. In a permutating switch of the class described, the combination with a plurality of sets of switch springs, the individual 85 springs of each set being disposed in different planes and alternatively adapted to be actuated into electrical contact, permutative normal connections therefor, an engaging member for said switch springs, electromagnetic means for effecting the relative movement of said switch-springs and member, and additional electromagnetic means for varying the final contact-making position of the switch springs, whereby a circuit 95 may be closed therethrough under predetermined conditions, substantially as set forth.

9. In a selective system of the class described, the combination with a source of electrical energy and suitable circuit-controlling apparatus at a central office, of line conductors leading therefrom, a plurality of stations connected thereto each of which is equipped with a permutating switch, comprising a plurality of switch springs arranged in sets and connected set by set in a distinctive manner, an engaging part adapted to effect the variable engagement of said switch springs, an electro-magnet and means operated thereby for effecting the relative movement of said elements, another electro-magnet and means operated thereby for varying the final position of certain of the contact springs, and a controlled signal-circuit connected with each permutating switch, whereby any of said stations may be selectively signaled under predetermined conditions of current transmission from the central office, substantially as set forth.

10. In a selective system of the class described, the combination with a source of electrical energy and suitable circuit-controlling apparatus at a central office, of line conductors leading therefrom, a plurality 125 of stations connected thereto each of which is equipped with a permutating switch, comprising a plurality of switch springs arranged in sets and connected set by set in a distinctive manner, an engaging part adapted to effect the variable engagement of said 130

- switch springs, an electro-magnet and means operated thereby for effecting the relative movement of said elements, another electro-magnet means operated thereby for varying 5 the final position of certain of the contact springs, electro-magnetic means for restoring said switch; all being connected for actuation over the two limbs of the line, and a controlled signal-circuit connected with 10 each permutating switch, whereby any of said stations may be selectively signaled under predetermined conditions of current transmission from the central office, substantially as set forth.
11. In apparatus of the class described, the combination with a permutating switch comprising a plurality of sets of contacts arranged for permutative connection, a circuit including an electro-magnet and means 15 operated thereby for effecting the engagement of the contacts of said switch set by set, and a second circuit including an electro-magnet for effecting the bodily movement of the sets of switch contacts, circuit 20 controlling apparatus associated with said circuits, and a source of electrical energy controlled thereby, substantially as set forth.
12. In a system of the class described, the combination with two operating circuits of 25 a plurality of switches; each comprising a plurality of sets of contacts, an electro-magnet connected with one circuit, and means operated thereby for effecting the bodily movement of said contacts, and a second 30 electro-magnet connected in the other circuit, and means for selecting certain contacts from each set, and closing all of said selected contacts in series as said bodily movement takes place, the selecting opera- 35
- tion being governed by the second electro-magnet, substantially as set forth. 40
13. A selective device comprising a plurality of sets of switch springs, electro-magnetic means for collectively controlling said plurality of sets of switch springs and electro-mechanical means, comprising an electro-magnet and a guide, for individually adjusting 45 said sets of switch springs, substantially as set forth.
14. A selective device comprising, a plurality of sets of switch springs movable *en masse*, electro-magnetic means for advancing said sets of switch springs *en masse*, electro-magnetic means for affecting said sets of springs individually, a guide for adjusting 50 said springs, and electro-magnetic means for restoring said sets of springs, substantially as set forth.
15. In an electrical selective signaling system, the combination with an operator's keyboard, and electro-magnetic means for automatically adjusting a plurality of sets of switch springs in sequential order, of a switch operatively connected therewith, comprising sets of switch springs, electro-magnetic means for controlling said sets of switch springs *en masse*, and electro-mechanical means comprising an electro-magnet, and a guide for adjusting said sets of switch springs individually, substantially as 55 set forth. 60
